UNITED STATES PATENT OFFICE.

GEORGE A. TAFF, OF COLORADO SPRINGS, COLORADO.

HYDROCARBON-ENGINE.

1,048,760.

Specification of Letters Patent. Patented Dec. 31, 1912.

Application filed September 13, 1909. Serial No. 517,380.

To all whom it may concern:

Be it known that I, GEORGE A. TAFF, a citizen of the United States, residing at Colorado Springs, in the county of El Paso and State of Colorado, have invented certain new and useful Improvements in Hydrocarbon-Engines, of which the following is a specification, reference being had to the accompanying drawings, forming part 10 of this specification.

My invention has for its principal object the increase in the efficiency of hydro-carbon engines of the two-cycle type by providing for a more complete expulsion 15 of the products of combustion from the piston-chamber, after each explosion, preparatory to the introduction of the next charge of hydro-carbon. Its novelty will be hereinafter set forth and more particularly 20 pointed out in the claims.

In the accompanying drawings Figure 1 is a vertical section of a pair of hydro-carbon engines embodying my invention in approximately the plane of the axis of the 25 crank-shaft, the pistons and rods and cranks and crank-shaft being shown in elevation; Fig. 2 a middle vertical cross-section of one of said engines on the line 2—2 of Fig. 1, with the piston and rod and crank in 30 elevation; and Fig. 3 a horizontal cross-section of the pair of engines on approximately the line 3—3 of Figs. 1 and 2.

The same letters of reference are used to indicate corresponding parts in the several 35 views.

As shown in Fig. 1, I have illustrated my invention as embodied in a pair of engine units A A' having their cylinders B B' and the upper halves of their crank-casings 40 formed in the same integral casting. Each cylinder is provided with two piston chambers C D and C' D', of different diameters, the upper ones constituting the working cylinders of the engines and receiving 45 the working pistons E E', and the lower ones constituting supplemental air-compressing cylinders within which work the pistons F F' consisting of enlarged heads upon the lower ends of the pistons 50 E E'.

The extreme upper ends of the piston chambers C C' are slightly enlarged and form the combustion chambers e e'. Each 55 of these combustion chambers communicates, in the present instance, by a lateral passage a with the exhaust outlet b which is

controlled by an exhaust valve e normally held closed by a spring f and opened at the proper time for the exhaust by a tappet or cam g upon the rotary cam-shaft h.

The two crank-casings G and G' are separated from each other by a suitable division wall H, and each is provided with a spring-seated inlet valve I controlling an inlet opening which in the present instance is shown covered by a strainer or woven wire hood J. The tension of the springs which normally hold the valves I against their seats is such that the valves readily open to admit air to the crank-casings upon the reduction of the air pressure within the latter at the upward strokes of the pistons, while at their downward strokes the excess of pressure in said casings simply serves to hold the valves more firmly to their 75 seats.

Formed in the cylinder castings immediately beneath the working cylinders C C' are two annular chambers K K', each of which communicates at its upper end with the corresponding working cylinder by a series of ports L L'; and each of the annular chambers K K' is in direct communication with the crank-easing of the corresponding engine by vertical passages M M', Fig. 3, formed in the cylinder castings.

Each of the annular chambers K K' is connected by a diagonal cross passage, N N', Fig. 1, with the compression chamber or cylinder D or D' of the opposite engine. Thus, as shown in Fig. 1, the chamber D of the left-hand engine A is connected at its upper end by the diagonal cross passage N with the annular chamber K' of the right-hand engine A'; while the compression chamber D' of the latter engine is connected with the annular chamber K of the left-hand engine by the cross passage N' shown in dotted lines in said figure.

The crank easing, the vertical passages M M and the annular chamber K together constitute the compressed air chamber of the left-hand unit and similarly the crank easing G', passages M' M' and annular chamber K' constitute the compressed air chamber of the right-hand unit.

The pressure areas of the undersides of the supplemental pistons F F' are in the present instance approximately fifty per cent. greater than those of the upper ends of the pistons E E', with the result that a full downward stroke of either piston

will displace and force into the crank-casing beneath it a volume of air equal to one and one-half times the capacity of the working cylinder C or C' of such engine, and at the same time cause a volume of air equaling one-half the capacity of such working cylinder to be drawn into the compression cylinder D or D', above the piston F or F'.
 10 Under this construction and arrangement of the parts the operation of the engine, and the function performed by my invention, are as follows: In the position of the parts shown in Fig. 1 the piston of the left-hand engine may be assumed to have just completed its downward stroke, and the piston of the right-hand engine its upward stroke. At such downward movement the supplemental piston F of the left-hand engine has
 15 forced into the crank casing G beneath it a volume of air equaling one and one-half times the capacity of the working cylinder C. The only escape for this volume of air thus forced into the crank-casing by the
 20 downward movement of the piston is through the vertical passages M M to the annular chamber K, Figure 3, the outlet from which, through the ports L, is closed by the body of the piston until the latter
 25 approaches the limit of its downward movement and uncovers said ports. The air displaced during the downward movement of the piston is therefore compressed into the crank-casing beneath the piston and in the
 30 vertical passages M M and annular chamber K, such displaced volume of air, as before stated, being approximately fifty per cent. greater than the capacity of the working cylinder C. In addition to this volume
 35 of air compressed into the crank casing G and passages M M and annular chamber K by the downward movement of the piston of the left-hand engine, the upward movement of the piston of the right-hand engine has caused the supplemental piston F' to displace the air above it in the compression cylinder D' and force said air through the diagonal cross passage N' into the annular chamber K of the left-hand
 40 engine, thus adding to the volume of air compressed in the crank casing G, passages M M and annular chamber K, a further volume equaling one-half the capacity of the working cylinder C. Under these conditions, when the piston of the left-hand engine approaches the lower end of its stroke and uncovers the ports L, and the exhaust valve e of said engine is opened, as shown in Figs. 1 and 2, the air compressed in the
 45 crank casing G, passages M M and annular chamber K will immediately rush through the ports L into the working cylinder C, expelling the products of combustion therefrom and leaving in the working cylinder a
 50 volume of pure air. Inasmuch as the vol-

ume of air thus admitted to the working cylinder under pressure is equal to twice the capacity of the cylinder itself it follows that the products of combustion are not only very completely expelled from the cylinder, but 70 that approximately one-half of the volume of fresh air thus admitted to the cylinder also passes through it and out the exhaust, and thus serves to very completely scavenge the cylinder and clear it of all of the 75 foreign matter left in it by the preceding explosion. At the beginning of the upward movement of the piston of the left-hand engine and downward movement of that of the right-hand engine the ports L 80 at the lower end of the working cylinder of the left-hand engine will be closed by the piston itself, while the exhaust valve e will be closed by its spring f, Fig. 2, the cam g which has opened the valve passing from beneath the valve stem and permitting the spring to close the valve. The further upward movement of the piston will serve to compress the new charge of hydro-carbon in the working cylinder C, preparatory to the 90 next explosion. Such charge of hydro-carbon may be introduced into the working cylinder C, at the beginning of the upward stroke of the piston, in any suitable form and in any desired manner. I contemplate 95 introducing it into the cylinder in liquid form, through the inlet O, Fig. 2, and thereby dispensing with a carburetor, suitable provisions, unnecessary to be described in detail, being made for the purpose; but it 100 may be introduced in vapor form if desired. The charge, when introduced and compressed, will be ignited in the usual manner by an electric spark, the spark-plug being introduced at the opening P in the top of 105 the cylinder.

While I have described the operation resulting from the downward stroke of the piston of the left-hand engine and upward stroke of that of the right-hand engine, it 110 will be understood that precisely the same operation takes place, in reverse order, at the downward stroke of the piston of the right-hand engine and upward stroke of that of the left-hand engine, the air forced 115 into the crank casing G' of the right-hand engine at such time being compressed therein and in the vertical passages M' M' and annular chamber K' of the right-hand engine, and being supplemented by the air displaced from the compression cylinder D of the left-hand engine by the upward movement of the piston F' of that engine and forced through the diagonal cross passage N into the annular chamber K' of the right-hand engine, the whole volume of air rushing 120 into the working cylinder C' through the ports L' when the piston of the right-hand engine approaches the lower end of its stroke and uncovers said ports and the ex- 125

haust valve *e* of the right-hand engine is lifted and opened by its operating cam *g* upon the cam shaft *h*.

The working cylinders *C* and *C'* are shown 5 surrounded by the usual water jacket *C²*.

Having thus fully described my invention, I claim:

1. The combination of a pair of hydro-carbon engines, each comprising a working cylinder and piston, a supplemental cylinder and piston of larger diameter than the working cylinder and piston, the main and supplemental pistons moving in unison, a compressed air chamber into which the air 10 displaced by the supplemental piston at the working stroke of the engine is compressed, connecting passages and ports between said chamber and the working cylinder for admitting the compressed air to said cylinder 15 at the end of the working stroke of the piston, and cross-passages between the two units, each passage connecting the supplemental cylinder of one engine with the compressed air chamber of the other and permitting the air displaced from such supplemental cylinder by the return stroke of the piston to be forced into the compressed air chamber of the other engine to supplement the volume of air compressed therein by the 20 working stroke of its own piston:

2. The combination of a pair of hydro-carbon engines, each comprising a working cylinder and piston, a supplemental cylinder and piston of larger diameter than the 25 working cylinder and piston, the main and supplemental pistons moving in unison, a compressed air chamber into which the air displaced by the supplemental piston at the working stroke of the engine is compressed, 30 a self-opening inlet valve for admitting atmospheric air to said chamber at the return stroke of the piston, and connecting passages and ports between said chamber and the working cylinder for admitting the compressed air to said cylinder at the end 35 of the working stroke of the piston, and cross-passages between the two engines, each passage connecting the supplemental cylinder of one engine with the compressed air chamber of the other and permitting the 40 air chamber of the other and permitting the air displaced from such supplemental cylinder by the return stroke of the piston to be forced into the compressed air chamber of the other engine to supplement the volume of air compressed therein by the working 45 stroke of its own piston.

3. The combination of a pair of hydro-carbon engines, each comprising a working cylinder and piston, a supplemental cylinder and piston of larger diameter than the working cylinder and piston, the main and supplemental pistons moving in unison, a compressed air chamber into which the air 50 displaced by the supplemental piston at the working stroke of the engine is compressed,

connecting passages and ports between said chamber and the working cylinder for admitting the compressed air to one end of said cylinder at the end of the working stroke of the piston, and a valve controlling 70 an exhaust outlet from the opposite end of said cylinder, with means for opening said valve as the piston approaches the end of its working stroke and for closing it at its return stroke, and cross-passages between 75 the two engines, each passage connecting the supplemental cylinder of one engine with the compressed air chamber of the other and permitting the air displaced from such supplemental cylinder by the return stroke of the piston to be forced into the compressed air chamber of the other engine to supplement the volume of air compressed 80 therein by the working stroke of its own piston.

4. The combination of a pair of hydro-carbon engines, each comprising a working cylinder and piston, a supplemental cylinder and piston of larger diameter than the working cylinder and piston, the main and supplemental pistons moving in unison, a compressed air chamber into which the air displaced by the supplemental piston at the working stroke of the engine is compressed, 90 a self-opening inlet valve for admitting atmospheric air to said chamber at the return stroke of the piston, connecting passages and ports between said chamber and the working cylinder for admitting the compressed air into one end of said cylinder 100 at the end of the working stroke of the piston, and a valve controlling an exhaust outlet from the opposite end of said cylinder, with means for opening said valve as the piston approaches the end of its working 105 stroke and for closing it at its return stroke, and cross-passages between the two engines, each passage connecting the supplemental cylinder of one engine with the compressed air chamber of the other and permitting the 110 air displaced from such supplemental cylinder by the return stroke of the piston to be forced into the compressed air chamber of the other engine to supplement the volume of air compressed therein by the working 115 stroke of its own piston.

5. The combination of a pair of hydro-carbon engines, each comprising a working cylinder and piston, a closed crank-easing, a supplemental cylinder and piston located 120 between the working cylinder and piston and the crank-easing, and of larger diameter than the working cylinder and piston, the main and supplemental pistons moving in unison and the supplemental piston operating at the working stroke of the engine to force the air displaced by it into the crank-easing, and connecting passages and ports 125 between the crank-easing and the working cylinder for admitting the compressed air 130

to said cylinder at the end of the working stroke of the piston, and cross-passages between the two engines, each passage connecting the supplemental cylinder of its engine with the compressed air chamber of the other engine and permitting the air displaced in said supplemental cylinder by the return stroke of the piston to be forced into the compressed air chamber of the other engine and supplement the air compressed therein by the working stroke of its own piston.

6. The combination of a pair of hydro-carbon engines, each comprising a working cylinder and piston, a closed crank-casing, a supplemental cylinder and piston located between the working cylinder and piston and the crank-casing, and of larger diameter than the working cylinder and piston, the main and supplemental pistons moving in unison and the supplemental piston operating at the working stroke of the engine to force the air displaced by it into the crank-casing, connecting passages and ports between the crank-casing and the working cylinder for admitting the compressed air to one end of said cylinder at the end of the working stroke of the piston, and a valve controlling an exhaust outlet from the opposite end of said cylinder with means for opening said valve as the piston approaches the end of its working stroke and for closing it at its return stroke, and cross-passages between the two engines, each passage connecting the supplemental cylinder of its

engine with the compressed air chamber of the other engine and permitting the air displaced in said supplemental cylinder by the return stroke of the piston to be forced into the compressed air chamber of the other engine and supplement the air compressed therein by the working stroke of its own piston.

7. The combination of a pair of hydro-carbon engines A A', having the working cylinders C C' and working pistons E E', the supplemental cylinders D D' and supplemental pistons F F' moving with the pistons E E', the independent crank-casings G G' in open communication with the supplemental cylinders D D' beneath the pistons F F', the inlet valves I for said crank-casings, the annular chambers K K' connected with the working cylinders by the ports L L' normally closed by the working pistons but opened by them at the ends of their working strokes, the passages M M' connecting the crank-casings with the chambers K K', the exhaust valves e and means for opening them as the pistons approach the ends of their working strokes and closing them at their return strokes, and the cross passages N N' respectively connecting the supplemental cylinder D with the annular chamber K' and the supplemental cylinder D' with the annular chamber K.
